UNITED STATES PATENT OFFICE

THEOPHILUS G. WILLIAMS, OF MORRISTOWN, NEW JERSEY

SOUND AMPLIFIER

Application filed April 2, 1929. Serial No. 266,707.

This invention relates to means to amplify and propagate sound waves, particularly waves of the character transmitted by a diaphragm actuated by undulations induced in an electric current, as in a sound reproducing device, and particularly adapted for use in connection with radio receiving apparatus, and it is the object of the invention to provide a sound amplifier of this character, which is novel, compact and cheap in structure, and highly efficient in propagating and magnifying the sound waves of dominant and undertones.

In carrying out the invention I provide a resonance chamber having walls adapted to vibrate by and in consonance with sound waves transmitted thereinto, said chamber being in the nature of a horn substantially of truncated pyramidal form with the sound emitting opening at the larger end and a sound receiving opening at the smaller end, said chamber being formed of panels, preferably of relatively thin wood having alternate hard and soft or spongy growth rings and quarter sawed wherein the grain will extend in parallel and alternate hard and soft layers, with the panels supported at the edge portions practically without stress or strain, said horn with a sound receiving and transmitting chamber in communication with the sound receiving opening thereof being mounted in a casing or cabinet having an open side with the walls of the horn and cabinet in spaced relation and with the sound emitting opening of the horn arranged at and to conform to the contour of the open side of the cabinet.

In the drawing accompanying and forming a part of this specification, Figure 1 is a perspective view of my improved sound amplifier with a portion of the cabinet broken away to show the arrangement of the resonance and sound receiving chamber therein.

Figure 2 is a plan view with the cabinet in section.

Figure 3 is a front elevation with a portion of the wall of the resonance chamber broken away.

Figure 4 is a perspective view of the resonance chamber and connected sound receiving and transmitting chamber, partly broken

away to show the connection of said chambers; and

Figure 5 is an enlarged fragmentary view in perspective to show the manner of supporting the panels at the edge portions without stress or strain.

In the embodying of the invention illustrated in the drawing there is provided a cabinet or casing of rectangular shape and open at one side to constitute the front, as at 7, and having a resonance chamber or horn arranged therein with the wall thereof in spaced relation to the wall of the cabinet to provide an air space between the two to permit of free vibratory movement of the wall of the resonance chamber.

The resonance chamber is in the form of a truncated pyramid constructed and arranged of a plurality of triangular shaped panels, in the present instance four in number, 8, 9, 10 and 11, preferably of wood, such as spruce, having alternate layers of hard and soft or spongy growth rings and quarter sawed. These panels are connected and supported at the longitudinal edge portions practically without stress or strain by engaging the side edge portions in grooves, as shown at 12, extending longitudinally of ribs 13 and secured therein by a yielding gum or cement. The panels are so constructed and arranged that the edge portions about the larger or sound emitting opening are at and conform to the contour of the open side or front of the cabinet, with one corner, as 9^a, formed by a connection of one edge of panels 8 and 9 extending at a right angle to the open end of the horn and parallel to the corner 14 of the cabinet formed by a side 6^a and the bottom of the cabinet and in a direction toward the corner formed by said side 6^a and bottom 6^b and the back wall 6^c to a point where it meets a chamber 15 forming part of a sound wave receiving and transmitting passage or chamber to be hereinafter described. The panel 8 extends in parallel and spaced relation to the side 6^a of the cabinet with the front edge portion extending from the top to the bottom and the top edge inclined downward toward the back of the cabinet, as shown at 8^a. The panel 9 extends in parallel and spaced rela-

tion to the bottom 6^b with the front edge marginal portion extending to the adjacent opposite side wall of the cabinet, and the edge of said panel at which it is joined to the edge 5 portion of panel 10 through the rib 13 to form a corner 10^a inclining in a direction toward the side 6^a and back of the cabinet to the connection with the chamber 15. The panel 10 extends perpendicular to the panel 9 and 10 converges in a direction toward the panel 8 to a point where it merges with the chamber 15. The top edge of said panel 10 inclines downward at the same angle as the top edge 15 of panel 8. The juncture of panel 11 with panel 10 to form the corner 11^a is such that said corner converges in a direction toward the chamber 15. The panel 11 is of the same form as the panel 9 having one edge forming 20 with panel 8 the corner 8^a extending parallel to the side 6^a, while the opposite longitudinal edge with panel 10 forming the corner 11^a inclines in a direction toward the side 6^a and back of the cabinet from the opposite side thereof. By this arrangement of the panels 25 there is formed a resonance chamber substantially of pyramidal form having an outlet at the larger end and at the open side of the cabinet, said chamber also having a sound receiving opening, in the present instance 30 through the smaller truncated end of the chamber where it is connected with the chamber 15.

The chamber 15 is of rectangular form in cross section, although it could be of other 35 shape, and extends from adjacent the bottom of the cabinet toward the top thereof and has a portion 16 extending adjacent to the top and parallel therewith and the back toward the opposite side of the cabinet where 40 a further portion 17 of said chamber or passage extends along said side toward the front of the cabinet with a sound reproducing element in communication therewith, shown in a general way at 18, said element 45 including a diaphragm adapted to be vibrated either mechanically or by undulations in an electric current to transmit and transform said undulations into audible sound waves. The chamber is in the form of a 50 trumpet or horn, the portion 17 having substantially the same cross sectional dimension for the entire length thereof, while the portion 16 tapers or increases in cross sectional dimension from the juncture thereof 55 with the portion 17 to the portion 15. The chamber portions are of integral and rigid structure with the portions 15, which latter portion carries the resonance chamber formed by the panels 8, 9, 10 and 11 and 60 whereby said parts are mounted and supported in the cabinet free of and spaced from the walls of the cabinet. For this purpose the bottom wall of the chamber 15 is 65 of increased thickness or has a block 19

fixed thereto which is fixed to the bottom of the cabinet in a suitable manner.

In operation as the diaphragm of the sound reproducing element 18 is vibrated, either electrically or mechanically, the waves are transmitted from said diaphragm into and through the chambers 17, 16 and 15 and from the connection 20 thereof with the resonance chamber setting up a vibration of the panels of said chamber in consonance with the transmitted sound waves or vibrations, and by arranging said walls of quarter sawed wood having alternate hard and soft growth rings the dominant tones of such sound vibrations are magnified and the overtones absorbed. 75

By the construction and arrangement of a resonant chamber as described, a chamber of relatively small size will function to not only greatly amplify and propagate the sound waves transmitted thereto, but will also emit sounds of clear and natural tone due to the magnifying of the dominant tones and the absorbing of the undertones. 85

While there is illustrated and described a particular construction and arrangement of my improved sound amplifier, as by constructing the resonance chamber of four panels, it will be obvious that a greater or less number of panels may be utilized and come within the scope of the invention, the invention residing in the connecting and supporting of the panels at the longitudinal edge portions without stress or strain and the mounting of said chamber in a cabinet in spaced relation to the walls thereof whereby the walls of the chamber may have free vibration, and that variations may be resorted to and produce this result without departing from the scope of the invention. 95 100 105

Having thus described my invention, I claim:

1. In a sound amplifier, a cabinet of rectangular shape open at the front, and a horn within said cabinet constructed of panels connected at the side edge portions to form a chamber having a sound emitting opening of rectangular shape to conform to and at the open front of the cabinet, and a pair of panels extending at a right angle to each other and parallel to the bottom and a side of the cabinet and the connection of said pair of panels extending parallel to the corner of the cabinet formed by said side and bottom of the cabinet, and the connected edges of the other panels inclining from the front toward the back of the cabinet and converging in a direction toward the corner formed by the one side and bottom of the cabinet, and having a sound wave receiving opening at the terminus 110 115 120 125 130 135 of said converging corners and the corner of the panels arranged at a right angle.

2. In a sound amplifier, a cabinet of rectangular shape open at the front, and a horn within said cabinet constructed of panels con- 135

5 nected at the side edge portions to form a chamber having a sound emitting opening of rectangular shape at and conforming to the open front of the cabinet, one pair of panels extending parallel to the bottom and a side 10 of the cabinet and at a right angle to the corner formed by the panels and said corner extending parallel to the corner formed by said side and bottom of the cabinet, and the 15 corners formed by the connections of the other panels converging in a direction toward the right angle corner formed by the one pair of panels and in a direction toward the corner of the cabinet formed by the one side, bottom 20 and back toward which said latter corner of the horn extends, and said horn having a sound wave receiving opening.

25 3. In a sound amplifier as claimed in claim 1, means to support the horn at its truncated end by the cabinet with the horn panels free of the walls of the cabinet.

30 4. In a sound amplifier as claimed in claim 1, an elongated sound wave receiving and transmitting passage arranged within the cabinet and connected to the sound wave receiving opening of the horn.

35 5. In a sound amplifier as claimed in claim 1, a sound wave receiving and transmitting passage connected with the receiving opening of the horn, said passage extending from the corner of the cabinet toward which the horn panels extend and upward along one side toward the top of the cabinet, along the corner formed by the juncture of the top and 40 back of the cabinet to the opposite side and then along said side toward the front of the cabinet.

45 6. A sound amplifier as claimed in claim 1, wherein the panels of the horn are connected one with the other without stress or strain and supported in the cabinet with the horn panels free of the walls of the cabinet.

50 7. In a sound amplifier, a series of panels and grooved ribs interposed between them and in the grooves of which ribs edge portions of the panels are engaged to connect and support the panels without stress or strain, said panels and ribs being constructed and arranged to form a horn substantially of rectangle-pyramidal shape and having a sound receiving opening at the smaller end.

55 8. In a sound amplifier as claimed in claim 7, a cabinet having an open side in which the horn is mounted with the outlet opening at the open front of the cabinet and with the marginal portion of the horn outlet arranged to conform to the contour of and in spaced relation to the opening in the front of the cabinet.

60 9. In a sound amplifier as claimed in claim 7, an elongated sound receiving and transmitting chamber connected to the sound receiving opening of the horn, a cabinet having an open front and means to mount the chamber and horn in the cabinet with the outlet

65 of the horn at and arranged to conform to the contour of and spaced from the opening in the front of the cabinet and with the walls of the horn free of and in spaced relation to the walls of the cabinet.

70 10. In a sound amplifier, a horn of pyramidal form constructed of triangular panels of quarter sawed wood having alternate layers of soft and hard growth rings and connected at the longitudinal edge portions arranging the horn with an outlet at the larger end of rectangular form, two of said panels being connected to extend at a right angle, and the other panels connected to incline from the open end in a direction toward the panel opposed thereto, and the corner formed by the juncture of said panels converging from the open end in a direction toward the right angle corner formed by the first two panels.

75 Signed at New York city, in the county of New York and State of New York, this 31st day of March, A. D. 1928.
